UNITED STATES PATENT OFFICE.

FRANK J. HELMUTH, OF OAKLAND, CALIFORNIA.

LOCK.

Application filed March 17, 1926. Serial No. 95,340.

The present invention relates to improvements in locks and has particular reference to a door-lock. The principal object of the invention is to provide a lock of the character described that is particularly well constructed and difficult to open without the aid of a key made for the same.

A further object of the invention is to provide a novel operating mechanism for the lock bolt that is particularly effective and simple in construction.

A further object of the invention is to provide a novel tumbler arrangement particularly adapted for the purposes of my lock.

Further objects and advantages of my device will appear as the specification proceeds.

The preferred form of my invention is illustrated in the accompanying drawings in which

Figure 1 shows a front view of my lock,

Figure 2 is an end view of a door with my lock secured therein,

Figure 3 is a side view of a key ready for insertion into the lock of Figure 2,

Figure 4 is a transverse section through the tumbler arrangement,

Figures 5 and 6 are detail views graphically illustrating the co-operation between the key and tumblers,

Figure 7 is a longitudinal section through the tumbler arrangement,

Figure 8 is an end view thereof,

Figure 9 is a longitudinal section through a tubular element co-operating with the tumbler arrangement,

Figure 10 is an end view of the same,

Figure 11 is a front view of the bolt operating mechanism,

Figure 12 is a section taken along line 12—12 of Figure 11, and

Figure 13 is a detail view of a means for holding the tumbler housing against rotation.

While I have shown only the preferred form of the invention I wish to have it understood that various changes or modifications may be made within the scope of the claims attached hereto without departing from the spirit of the invention.

In its preferred form my lock comprises a tumbler arrangement accommodated in the tumbler housing 1 and the bolt operating mechanism arranged in the preferably rectangular flat case 2 adapted to be inserted into the edge of a door in a manner well

known in the art. The housing 1 is adapted for insertion through a transverse hole and to be threaded into the case after the latter has been inserted as shown at 3 in Figure 12. 60 The front end of the housing is provided with a slight conical flange 4 and receives before insertion a conical ring 6 adapted to bear on the plate 7 customarily arranged on doors in combination with locks of this character. The housing is firmly held against rotary motion by means of a set screw 8 introduced from the edge of the door through a hole in the plate 9 formed integral with the case 2 and this set screw extends through 65 a tube 11 disposed on the inside of the housing so that this tube is also held against rotary motion. The tube is provided with a plurality of longitudinal slots 12 connecting each with a transverse slot 13. A cylinder 70 14 is revolvable in this tube 11 but is held against endwise motion by means of a flange 16 bearing on the outer end of the tube 11 and seated in a recess 17 in the housing and at the inner end by a plate 18 secured to the 75 cylinder by means of screws 19.

The cylinder is formed with a plurality of radial slots 21 adapted to slidably receive registering flat tumblers 22 having pins 23 projecting forwardly therefrom and extending into small bores 24 through which prongs 26 of a key 27 may be inserted. The length of the pins 23 and the prongs 26 is such that when the key 27 is fully inserted the pins 23 and with them the tumblers 22 are pushed backward sufficiently far to allow outward projections 28 extending from the tumblers into the longitudinal slots 12 to register with the transverse slots 13 and to be pushed thereinto by a revolving motion of the key. 80 The latter is formed with a central guiding member 29 adapted for insertion in a perforation 31 in the cylinder for steadyng the key. The guide member is preferably notched as shown at 32 to allow a spring 33 85 to catch therein. Springs 34 guided by pins 36 tend to push the tumblers toward the front while a spiral spring 37 accommodated in a recess 38 within the cylinder 14 tends to return the cylinder to its initial position from a rotary excursion. The rotary motion of the cylinder is limited by a pin 35 extending from the rear edge of the housing and riding in a peripheral recess 40 formed in the plate 18. 90

A retractable dog 41 projects from the back plate 18 and has a spring 42 associated

therewith tending to force the same outwardly. This dog is used for transferring rotary motion from the cylinder 14 to the bolt operating mechanism shown in Figures 11 and 12, the dog engaging with a ratchet 43 and causing the ratchet to revolve with the same when turned in one direction. The ratchet is held against backward motion by a pawl 44 engaging with another ratchet 46 fixed relative to the ratchet 43 so that on the return motion of the cylinder 14 the dog 41 rides over the slanting face 47 of a ratchet tooth to engage with the other steep face thereof for the next turn. A disc 49 from which certain peripheral sections have been removed is fixed to the ratchet and has a plurality of symmetrical pins 51 depending from its peripheral section, each pin carrying a roller 52. A bolt 53 of conventional form is made slidably in the edge plate 9 and is formed with a rear extension plate 54 shaped to surround the rollers 52 and provided with two cam faces 56 and 57 adapted to be alternately engaged by the rollers 52. In the position shown in Figure 11 one of the rollers 52 is just about to pass the cam 56 for forcing the plate 54 into an extreme backward position. Continuation of rotary motion forces the plate further backward until the front face of the bolt 53 is flush with the front face of the plate 9 at which time the roller passes the point of 56 and the disc 49 comes to a standstill due to the fact that the cylinder 14 has reached the limit of its rotary movement. In this position another roller 52 is ready to attack the cam face 57 upon a new turning motion of the cylinder 14 whereby the bolt 53 is thrown outwardly into engagement with a socket provided in the frame to which the door is to be locked. When passing the cam 57 the roller 52 responsible for the last bolt movement, engages, due to the action of a spring 59, in a notch 61 for holding the bolt 53 against rearward motion. It is apparent that at this time the roller 52 is right in the path of the bolt and the latter is effectively prevented from being forced backward. A spring 62 adapted to drop into a notch 63 at the front edge of the plate 64 yieldingly locks the said plate in the said rearward position. The plate may be guided in any suitable manner as between two abutments 64 and clips 66 extending over the same from the abutments.

The operation of my locking device is as follows: To unlock the same a key is inserted and pushes the tumblers 22 backward over the resistance of the springs 34 until the projecting prongs 28 register with the transverse slots 13 in the tube 11 whereupon a turning movement is executed against the opposition of the spring 37, the turning movement being limited by the pin 35. This turning movement is transferred to the

ratchet 43 by the dog 41 and causes the ratchet to advance by the length of one tooth. The door being locked one of the rollers 52 is disposed in front of the cam 56 and revolving motion of the ratchet 43 causes the said roller 52 to ride on the cam 56 and to push the plate 54 backward and with it the bolt 53, the plate being held in position by means of the spring 62. As the operator releases the key the cylinder 14 returns to its initial position due to the action of the spring 37, while the dog 41 climbs over the slanting face 47 of the next tooth for engagement with the steep face 48 thereof. The return of the cylinder to its initial position causes the projections 28 to again register with the longitudinal slots 12 and the tube 11 and allows the tumblers to return to their initial position due to the action of the springs 34.

The door is now unlocked and to lock the same a new turning motion of the key is necessary which again advances the ratchet 43 by one step. During this step one of the rollers 52 engages with the cam 57 and forces the plate forward whereby the bolt 53 is engaged with a recess in the frame to which the door is to be locked. In pushing the bolt 53 forward the spring 59 is placed under tension and forces the bolt back as soon as the roller 52 has passed the tip of the cam 57 for catching the roller in the notch 61 whereby the bolt 53 is firmly held in a locked position. The spring 37 again returns the cylinder 14 to its initial position and allows the springs 34 to return the tumblers 22.

I claim:

1. In a lock of the character described, a reciprocable bolt, a revolvable element, means for advancing the revolving element in measured steps and means associated with the latter for alternately moving the bolt backward and forward.

2. In a lock of the character described, a reciprocable bolt, a revolvable element, means for advancing the revolving element in measured steps and means associated with the latter for alternately moving the bolt backward and forward and for automatically locking the bolt in its advance position.

3. A device as defined in claim 1 in which the means for advancing the revolving element are key-operated and automatic means for returning the key operated means to an initial position after each advance.

4. A device as defined in claim 1 in which the means for advancing the revolving element comprise a ratchet fixed relative to the latter, a retractable pin engaging with the teeth thereof and means for step-wise revolving the pin and means for automatically returning the pin to an initial position after each advance.

5. A lock comprising a bolt actuating mem- 230

ber intermittently rotatable in one direction and an oscillatable key actuated member operatively connected to said bolt moving member.

5 6. A lock comprising a bolt actuating member intermittently rotatable in one direction and an oscillatable key actuated member operatively connected to said bolt moving member, and positive means for preventing the 10 return movement of said bolt actuating member after it has been advanced one step.

7. A lock comprising a bolt, a bolt actuating member intermittently rotatable in one direction for selectively moving said bolt 15 into locking position and into unlocked position, an oscillating key actuating member for advancing said bolt actuating member step by step, said member being adapted to be rotatable in one direction by a key for 20 moving said bolt into locked position or into unlocked position.

8. A lock comprising a bolt, a bolt actuating member intermittently rotatable in one direction for selectively moving said bolt 25 into locking position and into unlocked position, an oscillating key actuating member for advancing said bolt actuating member step by step, said member being adapted to be rotated in one direction by a key to move 30 said bolt into locked position or into unlocked position, and positive means for preventing the return movement of said bolt actuating member.

9. A lock comprising a bolt, a bolt moving member having a locking nut in alignment 35 with the path of movement of said bolt, and an intermittently rotatable bolt moving member having its axis cutting thru a line drawn between the notch and the bolt, and means carried by said rotatable member and 40 receivable in said notch for securing the bolt in locked position.

10. A lock comprising a casing, a bolt formed with a rear frame presenting two cam faces, a revolving element, spaced rollers carried by said element for alternately advancing and retracting said bolt while the revolving element is intermittently rotated in one direction, said frame having a notch 45 for receiving said rollers in dead center position with respect to the path of movement of said bolt.

11. A lock comprising a casing, a bolt formed with a rear frame presenting two 55 cam faces, a revolving element, spaced rollers carried by said element for alternately advancing and retracting said bolt while the revolving element is intermittently rotated in one direction, said frame having a notch for receiving said rollers in dead center position with respect to the path of movement of said bolt, and positive means for preventing 60 the return movement of said revolving element.

In testimony whereof I affix my signature.
FRANK J. HELMUTH.
